UNITED STATES PATENT OFFICE.

ANDREW J. NELSON AND ELMER M. NELSON, OF ST. PAUL, MINNESOTA.

BOAT-PROPELLING DEVICE.

Application filed December 6, 1922. Serial No. 605,183.

To all whom it may concern:

Be it known that we, ANDREW J. NELSON and ELMER M. NELSON, citizens of the United States, residing at St. Paul, in the 5 county of Ramsey and State of Minnesota, have invented certain new and useful Improvements in Boat-Propelling Devices, of which the following is a specification.

Our invention relates to propelling mechanisms for boats and vessels. The object is to provide power driven boats with a propelling device that obviates the tendency of earlier propelling devices, like propellers and paddle wheels, to get entangled in weeds, and also to waste much power by pressing downward and upward 10 in the water which of course does not serve to propel the boat as can readily be understood by looking at a paddle wheel how it presses deep cavities in the water before pulling forward at all, and after some pulling must be forced to the surface and raise great quantities of water above the surface.

As for a regular propeller it is obvious that 25 it wastes much power in being rotated and only a portion of the power is, by the incline of the wings, converted into actual propulsion of the boat.

In the accompanying drawing:

30 Fig. 1 is a plan or top view of a power driven boat equipped with our new propelling device.

Fig. 2 is an enlarged side elevation of the rear portion of the boat in Fig. 1.

35 Fig. 3 is an enlarged top view of one of the water engaging devices of the apparatus.

Fig. 4 is a left end view of Fig. 3.

Fig. 5 is a side view of Fig. 3.

40 Fig. 6 is an edge view of one of the paddles modified.

Referring to the drawing by reference numerals, 7 designates a boat or vessel to be propelled by motive power which may be of any suitable kind, but we have illustrated the same by two steam cylinders 8 receiving steam through piping 9 from a steam boiler (not shown). 10 indicates a bed-plate secured at 11 upon the boat and having rearwardly directed arms 12, the rear end of which have journal boxes 13 for a multiple crank shaft 14, the ends of which are each provided with a crank 15 driven by a connecting rod 16 and a piston rod 17 in one of the cylinders 9, the latter being also preferably secured upon the same bed plates 10

but may also have special bed plates of their own.

Secured upon the bed plate 10 are a series of bearings 18 in which slide several parallel 60 rods 19 each of which has secured to its rear end by a joint 20 a bar 21 having a journal box 22 engaged by one of the cranks 23 of the shaft 14.

Each bar 21 has its rear end provided 65 with a paddle plate 24 fixed at about right angles to the bar and preferably curved in horizontal direction and having its upper corners sloping as at 25 in Fig. 4 to prevent their catching and lifting of sea weed 70 or other obstructions in the water.

When these paddles (24) are large they 75 may have braces about as 26 in Figs. 3 and 5 and may be secured to the paddle bars 21 by transverse angle irons 27 or in any other suitable manner. The bars 21 may also be of any suitable material and form in cross section, but ordinarily it is believed that I-beams will be preferable and we have therefore indicated them as such in the drawing. 80

In the operation, when the boat is to travel forward, the crank shaft is rotated in the direction of the arrow 28 in Fig. 2, whereby the paddles are in successive alternate order plunged edgewise down into 85 the water and forced rearwardly until escaping edgewise upwardly out of the water and are then brought forward above the shaft and again plunged into the water.

In stopping or reversing the movement of 90 the boat the engine is reversed and the paddles thereby caused to move in the reverse direction. If the paddles are curved as shown they will not get as good a hold in the water when working backward as 95 when pushing forward, but they get hold enough for the purpose in question.

In special cases if it be desired to have the propelling device at the front end of the boat, so as to break up thin ice in front of 100 the moving boat, the paddles are reversed with the concave side toward the boat and their lower edges are chisel shaped as shown at 24* in Fig. 6. In the latter view it is also indicated that the paddles may be flat 105 and not arched.

What we claim is:

1. The combination with a boat or vessel and suitable frame work thereon of a multiple crank shaft journaled across one end 110 of the boat, a series of normally vertically disposed paddles, a series of paddle bars

each with one end fixed to one of the paddles and having its body journaled to one of the cranks of the shaft, a series of rods guided to slide horizontally and having each one 5 end pivotally connected to one of the paddle bars, and means for rotating the crank shaft.

2. The structure specified in claim 1, in which the paddles are arched in horizontal 10 direction to form a concave surface on the side mainly used for propulsion.

3. The structure specified in claim 1, said paddles having their corners slanted so as not to catch and lift sea-weed or like matter.

4. The structure specified in claim 1, said 15 paddle bars having lateral braces securing them to the paddles.

5. The structure specified in claim 1, said 20 rotating means comprising a crank fixed at each end of the multiple crank shaft and a steam engine having two cylinders each with a piston rod and pitman connecting it with one of the said end cranks.

In testimony whereof we affix our signatures.

ANDREW J. NELSON.
ELMER M. NELSON.
